ADOLPH FREES, OF THORNWOOD, AND ALFRED COX, OF HAWTHORNE, NEW YORK.

AUTOMATIC STOP AND SPEED CONTROL FOR RAILWAY-TRAINS AND THE LIKE.

1,171,112.

Specification of Letters Patent.

Patented Feb. 8, 1916.

Application filed March 24, 1915. Serial No. 16,568.

To all whom it may concern:

Be it known that we, ADOLPH FREES and ALFRED COX, both citizens of the United States of America, and residents, respectively, of Thornwood, Westchester county, New York, and Hawthorne, Westchester county, New York, have invented certain new and useful Improvements in Automatic Stops and Speed Control for Railway-
10 Trains and the like, of which the following is a full, clear, and exact specification.

Our invention relates to automatic stops and speed control for railway trains and the like and one object of the invention is to provide a device which will be operated when the track signal stands at "danger" and the speed of the train is greater than a predetermined speed. When the train is moving at a rate in excess of say six miles an hour it may be considered to be out of control and if our device is set to operate when the rate of speed exceeds such predetermined rate of speed, then, if the track signal is set at "danger" the air brakes will be operated and the train stopped.

Another object is to provide a device which will be set to operate when a cross-over switch is opened and the train is moving at a rate of speed exceeding such predetermined rate of speed. We thus provide a means which will stop the train automatically under the given conditions but will not so operate when the speed is such that the train is safely under control.

35 In the following we have described, in connection with the accompanying drawings, a form of device, with modifications, illustrating a way of carrying the principles of our invention into practice, the features 40 thereof being more particularly pointed out hereinafter in the claims.

Figure 1 of the drawings is a perspective view of an arrangement of means for carrying out our invention, parts being broken away; Fig. 2 is a fragmentary perspective view of a modification; and Fig. 3 is a perspective view of the track portion of the invention shown in connection with a cross-over switch.

50 In the drawings 1 and 2 indicate the beams of a railway truck, carried by the axle 3 of the car in any convenient manner (not shown).

4 is one of the wheels.

55 5 is a strap or support carried by beams 1 and 2.

6 and 7 indicate respectively a pump and a tank, for light oil or other suitable preferably non-freezing fluid, supported by strap 5. The pump is shown as adapted to be actuated by plunger rod 8 carrying collar 9, driven by a cam 10 on axle 3.

11 is a cylinder provided with a weighted piston 12, carrying piston rod 13 connected at its upper end (Fig. 1) to a bell-crank lever 14 pivoted at 15 to beam 1. The bell-crank lever 14 at its free end is adapted to engage a transverse rod 16 adapted to slide across beam 1 under straps 17, 17. Finger 18, at the outer end of rod 16, is adapted to engage the inner end of a sliding plate 19, slotted at 20 to receive the valve stem 21 of air brake valve 22 on air train-pipe 23.

24 indicates a contact plate on the outer end of sliding plate 19.

75 The track signal comprises an arm 25 carrying a contact plate 26. Arm 25 is rotatably mounted on a rod 27 in bearings in cover 28 of housing 29 and in floor 30 of the housing and is rigidly secured to arm 31, in turn loosely linked to arm 32 loosely connected to one end of bell-crank lever 33 pivoted to arm 34 carried by the housing or other convenient support. The other end of bell-crank lever 33 carries a weight 35 and is adapted to be raised by sprocket chain 36 actuated by the armature of motor 37 in the well-known manner, the commutator of the motor being so arranged that when current is on and the weight 35 raised the armature 90 ceases rotation.

38 is a pipe carrying track relay wires 39.

The full lines in Fig. 1 show the track signal with current off and signal at "danger", the dotted lines showing the current 95 on and the signal "clear".

40 indicates the exit pipe from pump 6 to cylinder 11, 41 the return pipe from cylinder 11 to tank 7 and 42 the pipe from tank 7 to pump 6.

100 43 indicates a by-pass connection from cylinder 11 to return pipe 41 and 44 a valve for controlling the passage of fluid through by-pass 43.

105 The operation of the device illustrated in Fig. 1 is as follows: The moving of the train through the rotation of axle 3 actuates pump 6 to draw fluid from tank 7 and to force it through pipe 40 into cylinder 11. Weighted piston 12 is of such dimension 110 and weight that the pressure caused by the fluid, when pump 6 is actuated at slow

speed, say six miles an hour, is not sufficient to cause the same to be raised, the fluid returning to tank 7 through pipe 41. When the speed exceeds the predetermined speed, 5 the pressure of the fluid raises piston 12 and operates bell-crank lever 14 to throw contact plate 24 out into the path of contact plate 26 of the track signal. When in this position the pressure in cylinder 11 is such 10 as to open valve 44 in by-pass pipe 43, or otherwise permit fluid to escape through pipe 43 and permit the pressure to be relieved while maintaining piston 12 at its upper position. The by-pass pipe 43 is thus 15 a pressure relieving pipe and is designed to relieve the excess pressure which would otherwise occur, if the piston had been forced its full limit and the speed of the train and consequently the pressure still 20 further increased. As the train slows down to the predetermined speed or less, the piston 12 falls and withdraws contact plate 24 from the path of contact plate 26. If now 25 when contact plate 24 is thrown out into the path of contact plate 26, the track signal being set at danger, as indicated by full lines, plate 26 will strike plate 24 and swing the same and air valve 22 to operate the valve and stop the train. The plate 24 and 30 the air valve will then have to be reset by hand before the train can proceed. If the track signal stands at "clear," as shown by dotted lines, the plates 24 and 26 will not contact and the air valve will consequently 35 not be operated.

In Fig. 2, a modification is shown in which the sliding plate 45 (corresponding to sliding plate 19, Fig. 1) is shown as vertically disposed and adapted to be actuated 40 by the rocking of a rod 46, pivoted at any convenient place, for example, on one of the beams of the truck, in turn actuated by the reciprocation of piston rod 13 of cylinder 11. Here the valve stem 21 of air brake 45 valve 22 stands horizontally. The remainder of the construction and the general mode of operation of the modification of Fig. 2 is the same as heretofore described in connection with Fig. 1, contact plate 24 being 50 actuated by contact plate 26 to operate the air valve and stop the train.

In Fig. 3 the track signal is shown as being manually operated by the same movement which opens the cross-over switch 47. 55 In Fig. 3, 48 indicates the switch controlling rod, 49 a bell-crank lever, pivoted at 50 to any convenient support, one arm of lever 49 being pinned to rod 48 and the other to rod 51. The other end of rod 51 is loosely 60 connected to arm 31, rigidly carried by rod 27, suitably journaled in housing 52 and carrying arm 25 provided with a contact plate 26, as hereinbefore described. In this form the act of opening the switch will set 65 the contact plate at "danger" so that a train

provided with our system will be brought to a stop if attempt is made to pass the switch at a speed higher than the predetermined rate of speed. As this is a frequent cause of accident, our invention forms a simple 70 and effective way of avoiding such.

It will be noted that in either of the forms shown, during the running of the train, the sliding plate 19 or 45 will reciprocate freely over the air valve without operating the 75 same, the plate being extended or retracted according to the speed.

It is obvious that the particular means described may be greatly varied without departing from the spirit of our invention, the 80 sliding plate 19 or 45 being operable horizontally, vertically, or in other convenient manner, the track signal being set either electrically or manually or by other convenient method and the particular form of the 85 various parts being unessential, and we do not restrict ourselves to any of the means shown and described further than the scope of the appended claims demands.

We claim:

1. In an automatic stop and speed control for railway trains and the like, means for actuating the air brake valve comprising a slotted plate adapted to reciprocate across the valve stem without actuating the 90 valve, a contact device carried by said plate, a rod adapted to engage said plate, a closed circuit liquid operated means adapted to actuate said rod and controlled in the extent of its action by the speed of the train, 100 a second contact device mounted adjacent the track and in the line of travel of said first contact device and means for moving said second contact device into and out of the path of said first contact device, the 105 valve being operated by the angular displacement of the slotted plate relative to the valve.

2. In an automatic stop and speed control for railway trains and the like, means for actuating the air brake valve comprising a slotted plate adapted to reciprocate across the valve stem without actuating the 110 valve, a contact device carried by said plate, a rod adapted to engage said plate, a lever adapted to actuate said rod, a plunger on one arm of said lever, liquid in a closed circuit controlling the action of said plunger, means controlled by the speed of the train for varying the pressure of said liquid, a 120 second contact device mounted adjacent the track and in the line of travel of said first contact device and means for moving said second contact device into and out of the path of said first contact device, the valve 125 being operated by the angular displacement of the slotted plate relative to the valve.

3. In an automatic stop and speed control for railway trains and the like, an air brake valve, a contact device mounted on 130

the valve stem, a closed circuit liquid pressure controlled means for sliding the contact device relative to the valve stem without actuating the valve, means for varying 5 the liquid pressure controlled by the speed of the train and a second contact device mounted adjacent the track and in the line of travel of said first contact device, the valve being operated by the angular displacement of the first contact device relative to the valve.

4. In an automatic stop and speed control for railway trains and the like, an air brake valve, a contact device mounted on 15 the valve stem, a closed circuit liquid pressure controlled means for sliding the contact device relative to the valve stem without actuating the valve, means for varying the liquid pressure controlled by the speed 20 of the train, a second contact device mounted adjacent the track and in the line of travel of said first contact device and a switch controlling the movement of said second contact device into and out of said 25 line of travel of said first contact device, the valve being operated by the angular displacement of the first contact device relative to the valve.

Copies of this patent may be obtained for five cents each, by addressing the "Commissioner of Patents, Washington, D. C."

5. In an automatic stop and speed control for railway trains and the like, means 30 for actuating the air brake valve comprising an arm provided with a slot for receiving the valve stem of the valve, a contact plate carried by said arm, a rod for reciprocating said arm across said valve stem, 35 means for actuating said rod comprising a cylinder, a fluid-operated weighted piston therein, a connection between said piston and rod, a fluid tank in open connection with the cylinder, a pump in connection 40 with the tank for forcing fluid into the cylinder, means for driving the pump from one of the axles of the car and means permitting the slotted arm to be moved angularly relative to the valve when the arm 45 is in extended position, to actuate said valve.

In testimony whereof we have signed this specification in the presence of two subscribing witnesses.

ADOLPH FREES.
ALFRED COX.
